UNITED STATES PATENT OFFICE.

HENRY ADAM ALHEIT AND JOHN ANTON BOYKEN, OF NEW YORK, N. Y.

SANDING DEVICE FOR VEHICLES.

1,235,410.

Specification of Letters Patent. Patented July 31, 1917.

Application filed December 7, 1916. Serial No. 135,570.

To all whom it may concern:

Be it known that we, HENRY A. ALHEIT and JOHN A. BOYKEN, citizens of the United States, and residents of the city of New York, borough of Manhattan, in the county and State of New York, have invented a new and Improved Sanding Device for Vehicles, of which the following is a full, clear, and exact description.

10 This invention relates to sanding devices for vehicles and has for an object an improved construction whereby sand may be discharged at any time upon the traction surface in front of the wheels of any form 15 of vehicle whereby slipping or skidding is retarded or prevented.

Another object in view is to provide a sanding device for motor driven vehicles constructed so that the exhaust may be automatically turned on to the sanding device for forcing sand on the traction surface beneath the wheels of the vehicle at the time, and perhaps before, the brakes have been applied.

25 A still further object in view is to provide a sanding device for motor driven vehicles in which the exhaust from the motor will discharge the sand, and means for turning on the exhaust in the proper direction 30 will be applied automatically when the brake is being set.

In the accompanying drawings:

Figure 1 is a side view of part of a motor driven vehicle with certain parts broken away, the same being shown in connection with a sanding device embodying the invention.

Fig. 2 is a top plan view of the structure shown in Fig. 1.

40 Fig. 3 is an enlarged detail perspective view of an exhaust distributing device embodying certain features of the invention.

Fig. 4 is a longitudinal vertical section through a sand distributing well or trap.

45 Fig. 5 is a detail fragmentary side view on an enlarged scale of means for connecting the brake pedal with the operating rod used in shifting the exhaust, the same disclosing certain features of the invention.

50 Fig. 6 is a view similar to Fig. 5 but with certain parts shown in section and the remaining parts moved to an operative position.

Referring to the accompanying drawings

by numerals, 1 indicates a motor driven vehicle of any desired kind, said vehicle being provided with the usual brake pedal 2 and an exhaust muffler 3. A fitting 4 (Fig. 3) is provided in the exhaust pipe between the muffler 3 and the engine, said fitting having an inlet opening 5 for receiving exhaust from the engine and outlet openings 6 and 7, outlet opening 6 directing the exhaust to the muffler 3 while outlet opening 7 directs the exhaust through pipe 8 to a well or trap 9, shown in detail in Fig. 4. Arranged in the section 6' of fitting 4 is a butterfly valve 10 held in an open position when the butterfly valve 11 in section 7' is held closed. When the valve 10 is closed 70 valve 11 will be open, the connection between these valves being through the cranks 12 and 13 connected to their respective valves and a link 14. An arm 15 is connected with crank 13, said arm having a clevis 16 pivotally connected thereto, said clevis having in turn pivotally connected thereto the operating arm 17 and spring 18. One end of spring 18 is connected with the bracket 19 on section 7' whereby the parts 80 are normally held in the position shown in Fig. 3 so that the exhaust will pass into the muffler 3. However, when arm 17 is pulled in the direction of the arrow the exhaust will begin to pass into section 7', the amount of 85 exhaust being in proportion to the movement of the rod 17 and the subsequent movement of the valves 10 and 11.

The rod 17 extends to near the front of the machine or to some convenient point, as 90 shown in Figs. 1, 5, and 6, where it passes through a supporting bracket 20, said bracket having a slot 21 therein. An adjustable stop 22 is connected to the rod 17 so as to engage the stop 23 on the rod 24 when 95 the parts are moved to the position shown in Fig. 6, said movement being assisted by the spring 25 when the cam 26 is moved from the position shown in Fig. 5 to the position shown in Fig. 6. The cam 26 is 100 connected with a pivotally mounted rod 27, said rod carrying a crank 28. A cable or other connecting member 29 extends from crank 28 to a hand operated lever 30 adjacent the wheel 31 of the vehicle 1, whereby 105 the operator may at any time move the cam 26 out of the way, namely, to the position shown in Fig. 6. This will cause the rod 17

to move down under the action of gravity and also the action of spring 25 so that whenever rod 24 is pulled toward the front of the vehicle the stops 22 and 23 will be 5 come engaged and rod 17 will be moved in the direction of the arrow shown in Fig. 3.

The rod 24 is connected with the usual brake rod 32, as shown in dotted lines in Fig. 1, whereby whenever the pedal 2 is depressed for applying the brakes the rod 17 10 will be pulled provided member 30 has been operated for moving the cam 26 to the position shown in Fig. 6. In operating the pedal 2 there is usually some considerable 15 lost motion before the brake shoe engages the brake wheel, and this lost motion permits an appreciable movement of rod 17 before the brakes are applied, thus allowing a discharge of the exhaust through section 20 7' and pipe 8 a short time before the brakes are quickly applied. In fact, by forcing the pedal 2 downwardly somewhat and merely "feel" the brake as it is termed, sand may be applied, the rod 17 being moved as just 25 described. As soon as the exhaust is turned on to the section 7' and pipe 8 it will pass through the trap or well 9 and from thence to the Y-shaped fitting 33 where it is divided and passes through the pipes 34 and 35, 30 respectively, to the discharge nozzles 36 and 37. The nozzles 36 and 37 may be wide or any other shape preferred so as to produce a proper discharge of the sand against and in front of the wheels of the vehicle.

35 In order that the sand may be brought into the path of movement of the exhaust from pipe 8 in comparatively small quantities, the well or trap 9 is provided with a projection 38 through which the end of a 40 pipe 39 passes, said pipe being clamped against accidental movement by a set screw 40. It will be observed that the well or trap 9 has a downwardly extending section 41 in which the clean-out plug 42 is fitted whereby 45 a cup structure is produced for receiving sand through pipe 34, thus preventing more than a small quantity of sand from entering the trap 9. When the sand has filled up the trap 9 to approximately the lower end of 50 the pipe 39 the sand will cease to flow. However, when the exhaust is turned on to the pipe 8 the same will pass through the well 9 and strike the sand therein whereby 55 said sand is distributed in a loose state to the pipes 34 and 35 and from thence to the nozzles 36 and 37. New sand is being continually supplied from pipe 39 as long as the exhaust is passing through the trap but as soon as the exhaust is turned off the trap 60 fills partially as above described and then the sand ceases to flow. Any suitable tank or reservoir may be provided for supplying the pipe 39 with sand, as for instance, the tank 43 shown in Fig. 1, said tank being supported in any suitable way, as for instance,

by pipe 39, though the pipe could be supported by the body of the vehicle and a telescoping pipe fitted within the pipe 39.

What we claim is:

1. A sanding device for vehicles, comprising a plurality of sand distributing pipes, a trap connected with said pipes, a sand-supply pipe extending into said trap and projecting to near the bottom thereof, means for clamping said supply pipe in any 70 adjusted position, tubular members for connecting said trap with the exhaust pipe of the engine of said vehicle, a valve arranged in said tubular members, and means for connecting said valve with the brake pedal 75 of the vehicle whereby when the brake pedal is operated the valve will be opened for turning on the exhaust so that the same will blow the sand from the trap into said distributing pipes. 85

2. A sanding device for motor vehicles, comprising sand distributing members for distributing the sand to points adjacent the wheels of the vehicle, a trap connected with said distributing members, means for supplying said trap with a predetermined quantity of sand, means for connecting the trap with the exhaust of the engine of said vehicle, said means including a fitting provided with two discharge passageways, one 90 leading to the trap and the other to the muffler of the vehicle, a valve arranged in each discharge passageway, means connecting said valves acting as operating means, said connecting means holding the valves 100 so that one is open while the other is closed, and means for connecting the operating means with the brake pedal of the vehicle whereby when the brake pedal is operated for applying the brakes said operating 105 means will shift the position of said valves so that the valve to the muffler will be shut off and the valve to the trap will be opened, thus allowing the exhaust to pass through the trap and force the sand therefrom to 110 said distributing members.

3. A sanding device for motor vehicles comprising a plurality of distributing pipes, means for supplying a predetermined quantity of sand adjacent said distributing pipes, 115 and means for switching on the exhaust from the engine of the vehicle so that the exhaust will blow said predetermined quantity of sand through the distributing pipes, said means including a Y fitting, a butterfly 120 valve in each arm of the Y and means for connecting said valves so that one will be opened when the other is closed.

4. A sanding device for vehicles, comprising sand distributing pipes, a supply trap, 125 means for continually providing a predetermined quantity of sand to said trap, means for directing the exhaust from the engine of said vehicle to the trap for blowing the sand into said distributing pipes, and operating 130

members for actuating said last mentioned means, said operating members including a rod provided with a stop, means for guiding said rod in a reciprocating motion and in an 5 up and down motion, a stop connected to the brake rod of the vehicle, and a manually operated cam for normally holding the first mentioned rod in such position as to prevent said stops from engaging, said stops when 10 engaging being designed to transmit power from the brake rod to the means for switching the exhaust to said trap.

5. A sanding device for motor driven vehicles, comprising sand distributing means, 15 a valve mechanism arranged to direct the exhaust from the engine of the vehicle to the sand distributing means for causing the operation thereof and to the muffler at will,

a rod for actuating said mechanism, a stop connected with said rod, a second stop connected with the brake rod designed to engage the first mentioned stop so as to move the same when the brake is being applied, said movement causing the exhaust to be switched from the muffler to the sand distributing means, a cam for normally holding the first mentioned rod so that the stop thereon will be held out of engagement with the second mentioned stop, and manually actuated means connected with said cam for 30 operating the same, said last mentioned means extending to near the steering wheel of the vehicle.

HENRY ADAM ALHEIT.
JOHN ANTON BOYKEN.
